DESIGN FOR A CIGARETTE LIGHTER

Price B. Miller, Kansas City, Mo., assignor to Miller Liter Company, Kansas City, Mo.

Application December 22, 1947, Serial No. 143,274

Term of patent 14 years

(Cl. D48—27)

To all whom it may concern:

Be it known that I, Price B. Miller, a citizen of the United States, residing at Kansas City, in the county of Jackson and State of Missouri, have invented a new, original, and ornamental Design for a Cigarette Lighter, of which the following is a specification, reference being had to the accompanying drawing, forming a part thereof.

Fig. 1 is a side elevational view of a cigarette lighter, showing my new design.

Fig. 2 is a side elevational view of the cigarette lighter, with the cap in an open position.

Fig. 3 is a front elevational view thereof.

Fig. 4 is a rear edge elevational view thereof; and

Fig. 5 is a top plan view thereof.

The drawing is shaded to indicate contrasting appearance.

I claim:

The ornamental design for a cigarette lighter, as shown and described.

PRICE B. MILLER.
